United States Patent Office

Des. 221,627
Patented Aug. 31, 1971

221,627

BOTTLE STOPPER

Harold Shapiro, 18160 Parthenia St.,
Northridge, Calif. 91324

Filed Nov. 3, 1969, Ser. No. 19,881

Term of patent 14 years

Int. Cl. D9—02

U.S. Cl. D9—254

FIG. 1

FIG. 2

FIG. 3

FIG. 4

FIG. 5

FIG. 1 is a front elevational view of a bottle stopper embodying my new design;

FIG. 2 is a rear elevational view thereof;

FIG. 3 is a side elevational view, the opposite side being a mirror image of the side shown;

FIG. 4 is a bottom plan view thereof; and,

FIG. 5 is a top plan view thereof.

I claim:

The ornamental design for a bottle stopper, as shown and described.
